CRACKING OF HYDROCARBON GASES AND HEATER THEREFOR

Otto C. Schauble, Mount Kisco, and Edward H. Patchik, Hollis, N. Y., assignors to The Lummus Company, New York, N. Y., a corporation of Delaware

Application September 20, 1952, Serial No. 310,592

5 Claims. (Cl. 260—679)

This invention relates to improvements in the heating of gases to conversion temperatures and more particularly to the thermal cracking of lower hydrocarbon gases such as methane, ethane and propane to obtain desired products such as ethylene and acetylene, for examples. It has been customary to employ for such cracking either heaters of the tube still type or those of the regenerative type. The former are quite expensive since they require the employment of expensive alloys in the tubes and their supports to withstand the high temperature required even for ethylene production. They are incapable of withstanding the higher temperature required for acetylene production so that a regenerative heater is employed for that purpose. An objection to an otherwise suitable regenerative heater is that it is cyclic and not continuous in its operation; the charge to the heater must be interrupted periodically for reheating of the heating surface or mass.

An important object of the present invention is to provide for the continuous performance of the aforesaid type of cracking with great economy in cost of heating apparatus and render possible the attainment of greatly increased temperature without damage to the apparatus and with acceleration of the reaction.

Other important objects of the invention are to provide a gas heater of improved design including a mass of refractory material having passages for continuously conducting there-through the charge to be converted and provision for directly and continuously firing said mass in a manner to effectively heat and convert the charge; to provide for controlling said firing in a manner to obtain a wide range of heat curves and adapt the heater for the conversion of different charges and to different degrees to obtain desired end products; and to provide means cooperable with said mass to limit the conversion by quenching.

Further objects and advantages of the invention will appear from the following description taken in connection with the accompanying drawings.

In the drawings:

Fig. 1 is a vertical longitudinal sectional view of the improved heater, the section being approximately on the line 1—1 of Fig. 2, with parts broken away and parts in elevation.

Fig. 2 is a vertical cross section on the line 2—2 of Fig. 1.

Fig. 3 is a horizontal section on the line 3—3 of Fig. 2; with most of the refractory appearing in plan.

Fig. 4 is a perspective view of one of the block components of the refractory mass.

According to the invention, the cracking operation is performed by a heater which includes an elongated mass of refractory material constructed of stacked blocks or tiles. The mass is formed with numerous passages extending longitudinally thereof and with numerous flues extending transversely of said passages and arranged in rows along the passages. The gas charge is passed continuously through the passages and the flues are continu-

2

ously fired by burners in respective alignment with the flues to heat the charge by conduction through the refractory material. The burners at different points along the charge passages are independently controllable to adjust the heat input with respect to the progress of the charge through the passages. Provision is also made for passing the combustion gas from some of the flues to others spaced along the course of the charge gas through the passages, for additional heat input. Certain of the flues near the end of the course of the charge may be left unfired for quenching the conversion reaction, and air may be directed into said flues for that purpose.

Referring to the drawings which show a preferred form of the heater, the refractory mass, designated M, is formed of a horizontal row of stacked blocks or tiles 1. One of these is shown in Fig. 4; it is of elongated rectangular shape and is formed with a central longitudinal flue 2 and with spaced transverse grooves 3 at its upper and lower faces. The block may, for example, be 8 inches square in cross section and 3 feet in length. The grooves 3 are omitted from the top faces of the uppermost blocks of the stacks and from the bottom faces of the lowermost blocks of the stacks. The blocks are otherwise duplicates of one another and they give the mass M an elongated rectangular form. Each block has adjacent each end thereof a groove 4 extending entirely around it. The grooves 4 are filled with a suitable cement, as indicated at 5 in Figs. 2 and 3, to seal all of the blocks together and prevent the escape of the charge gas at the opposite side faces of the mass M. The grooves 3 of abutting block faces together form passages for the charge gas. These passages extend throughout the length of the mass and the flues 2 extend throughout the width of the mass and are fired to heat the charge, as will be explained hereinafter.

The mass M is housed within a casing formed by a metal shell 6 lined with heat-insulating material 7 such as firebrick commonly employed in furnace walls. Actually, there will be courses of bricks but the heat insulation is shown as solid in order to simplify the illustration. The mass M rests upon the insulation at the bottom of the housing, and at the top of the housing, the insulation is passed down upon the mass by two rows of screw clamps 8 borne by a pair of beams 9 secured to columns 10 at opposite ends of the housing. A pair of the clamps bear upon the insulating lining over each stack or tier of blocks and serve to press the lining down upon the mass and press the blocks of the tier closely together. Horizontal pressure of the lining upon the mass is obtained from two vertical rows of screw clamps 11 borne by the columns 10 and bearing against the insulating firebrick to force it against the vertical side margins of the ends of the mass M, as shown in Fig. 3. The columns 10 extend beneath the housing to form short supporting legs for the heater unit. A structural steel frame 12 secured to said columns provides under support for the body of the heater. While the body of the heater is shown as vertical, it may be otherwise disposed.

The housing has an inlet 13 at one end to admit the gas charge to one end of the passages 3 and an outlet 14 at its opposite end to conduct reaction products from the opposite end of said passages. Said inlet and outlet are adapted to be connected to supply and discharge conduits, respectively. The interior of the housing is of substantially greater width than the width of the mass M and the latter is centered within the housing, to provide channels at opposite sides of the mass and extending the full length and height thereof. As shown in Fig. 3, partitions 15 divide these channels into compartments 16, 17, 18, 19, 20 and 21 in alternation at opposite sides of the mass. Compartment 21 has an exit flue 22 for combustion gas.

Provision is made for firing into the individual flues 2 of the refractory blocks 1. For that purpose, burners 23 are mounted in the side walls of the housing. These burners are disposed in alignment with the respective flues across the aforesaid channel compartments. For delivery of fluid fuel to the burners, there are two manifolds 24 leading from a supply source, not shown. Air for supporting combustion by the burners is delivered through two manifolds 25 connected to a source of compressed air, not shown. The burners are distributed upon the opposite side walls of the housing and the fuel manifolds and their companion air manifolds serve the burners upon the opposite walls, respectively. For the burners on each of said walls there are fuel and air mixers 26, one for each vertical row of burners for firing a stack or tier of the blocks. A pipe 27 leads from the respective fuel manifold to each mixer and a pipe 28 leads from the companion air manifold to the mixer. These pipes have valves 29. A riser pipe 30 leads from each mixer and branch pipes 31 lead therefrom to the individual burners of a vertical row of burners. The pipes 31 are provided with valves 32.

Thermostatic means are provided for indicating the temperature at different points along the mass M. At the top of the housing there is a row of thermocouples 33 each extending downward through the insulating firebrick and into contact with the topmost one of a stack of the blocks 1. The thermocouples are connected by wiring to a conventional type of device, not shown, for indicating the temperature of each of the stacks of blocks along the mass.

The opposite side walls of the furnace may, as shown, be formed of panels P which may be removed or swung outward to give access to internal parts for cleaning, repairing or replacement thereof, and the fuel pipes 30 are preferably formed of sections connected by releasable joints 34 to permit opening movement of the panels. Each panel extends for at least the full height of the refractory mass M and the total area of the panels at each side of the heater is at least equal to the side area of the refractory mass so that the mass may be fully exposed at either side. If desired, the panels may be provided with peep holes, not shown, for internal inspection of the heater during operation.

In the operation of the heater, the burners 23 are operated to fire into the flues 2 of the blocks 1 or selected ones of said flues. While the flame may or may not enter the flues, depending upon the adjustment of the burners, the combustion gas will be directly projected into the flues and the expression "fire into" is meant to apply both to entry of the flame and to such projection of the combustion gas. Referring to Fig. 3, the combustion gas from the burners at the channel compartment 16, after passing through the flues directly opposite said burners, enters the compartment 17 and is carried by the flame or gas from the burners at the compartment 17 into the flues fired by said burners. In a similar manner the combustion gas is passed in succession through the compartments 18, 19, 20 and 21 and the flues which open into the compartment. Each compartment, with the exception of compartment 21, has a group of the burners directed across it from one side or the other of the heater. Conduction of the combustion gas through groups of the flues in succession substantially increases the heat input over the direct firing by the burners. From the compartment 21 the combustion gas passes out of the heater through the outlet flue 22 which may lead directly to a stack or to a waste heat recovery means, not shown.

While the burners are operated, the gas charge to be converted is continuously conducted into the heater through the inlet 13 of the housing. Thence the charge passes continuously through the numerous parallel passages 3 in the refractory mass and is converted by heat conducted from the fired flues, through the refractory material, to the passages 3. The reaction products pass out

through the outlet 14. The heat input may be accurately adjusted to the particular charge employed and to the degree of conversion thereof desired by selective adjustment of the burners according to readings of the thermostatic indicator. The burners for firing the different stacks of blocks may be readily adjusted independently through adjustment of the fuel and air valves 29 to obtain any heat curve required. The reaction may also be quenched to limit the conversion by closing certain of the valves 29 to omit firing of some of the stacks of blocks, such as the ones located near the exit. Additional quenching effect may be obtained, if required, by closing the fuel valve 29 and opening the air valve in the pipe or line 28 to supply the respective burners with air to cool the selected stacks of blocks.

The heater disclosed may be constructed at a cost small in comparison with the cost of a tube type heater and, with the employment of a suitable refractory material in the blocks or tiles of the mass M, it may be operated at a temperature exceeding 3,000° F. without damage. At such temperature, cracking time is reduced so that conversion may be completed in a single passage of the charge through the refractory mass. Heaters of the regenerative type employing a refractory mass have been resorted to for exceedingly high temperature conversion which the tube type heaters are unable to withstand. Regenerative heaters are, however, not continuous in their conversion operation; said operation must be interrupted periodically to reheat the mass. The disclosed heater has the advantages of continuous conversion operation and improved control of heat input over a heater of the regenerative type. The heater is also designed for convenient operation and servicing, most of the parts being no more than breast high and internal parts being accessible. The charge passages 3 may be cleaned or decoked by a known method such as passing steam through them and operating the burners to superheat the steam.

If considered desirable for a particular heating or cracking operation, the flow of the charge gas may be reversed, passing in at 14 and out at 13. The flow of charge gas and combustion gas will then be generally concurrent.

While the advantageous employment of the heater for the cracking of hydrocarbon gases has been described, its utility is not limited to such employment. It may be employed to advantage for effecting synthesis reactions and for the conversion of charges other than hydrocarbon ones.

The present disclosure of the invention is merely illustrative and in nowise limiting and comprehends such modifications and adaptations as will come within the scope of the following claims.

We claim:

1. The method of thermally cracking a hydrocarbon gas charge, comprising passing said charge along substantially parallel courses confined by refractory material, firing transversely of said courses at points spaced therealong into flues defined by said material and separated thereby from said courses, firing transversely from the opposite side of said courses at points spaced therealong into a second group of flues defined by said material and separated thereby from said courses, passing the combustion gas of said firing from the exit end of one group of flues to the firing end of the next adjacent flues spaced along said course therefrom, conducting heat from said flues through said material to the charge within said courses, adjusting said firing at said spaced points on each side of said courses independently to obtain the desired cracking effect, and injecting air into a final group of flues spaced farther along said course than said firing points and defined by said material and separated thereby from said courses whereby heat is conducted away from said courses in the vicinity of said final flues to quench the cracking reaction in said courses.
2. A heater for a charge in a gaseous state, comprising a mass of refractory material formed with substantially

parallel passages for said charge and with substantially parallel transversely spaced flues open at both ends and in heat-conducting relation to said charge passages, through the refractory material of said mass, a plurality of independently controlled burners opposed to one end of some of said flues and the other end of the remainder of said flues respectively and directed to fire thereinto, and conduit means for conducting combustion gas from the opposite end of some of said flues to the fired end of others of said flues.

3. A heater for a charge in a gaseous state, comprising a mass of refractory material formed with substantially parallel passages for said charge and substantially parallel flues open at both ends extending transversely of said passages and spaced therealong and therefrom in heat-conducting relation to the passages, through the refractory material of the mass, burners opposed to one end of one portion of said flues and the other end of another portion of said flues respectively and directed to fire thereinto, means to control combustion at said burners independently, conduit means to conduct combustion gas from the opposite end of some of said flues to the fired end of others of the flues, and means to inject air into a remaining portion of the flues to cool them while others are being fired to heat the charge.

4. A heater for a charge in a gaseous state, comprising a mass of refractory material formed with substantially parallel spaced passages for said charge and flues open at both ends extending transversely of said passages and in heat-conducting relation thereto through the refractory material, said flues being transversely spaced in rows arranged successively along said charge passages and the latter extending between the tubes of said rows, burners opposed to one end of a portion of the flues and the other end of a portion of said flues respectively and di-

rected to fire thereinto, means to control combustion by said rows of burners independently, a heat insulating casing enclosing said refractory mass having an inlet for admission of the charge to one end of said passages and an outlet for discharge of the heated gaseous contents from the opposite end of the passages, the said casing having passages for conducting combustion gas from the opposite end of the flues of one portion of said rows to the fired end of another portion of the flues of said rows spaced along the charge passages, and outlet means for exit from said casing of combustion gas produced by the operation of the burners.

5. The heater of claim 4 including means for injecting air into a remaining portion of said flues to cool them while others are being fired to heat the charge.
